CENTRIFUGAL PUMP WITH INTERMITTENT
DISCHARGE

Robert H. Goddard, deceased, late of Annapolis,
Md., by Esther C. Goddard, executrix, Worcester,
Mass., assignor of one-half to The Daniel
and Florence Guggenheim Foundation, New
York, N. Y., a corporation of New York

Application February 1, 1947, Serial No. 725,803

1 Claim. (Cl. 103—103)

1

This invention relates to a centrifugal pump particularly adapted for use in feeding combustion liquids to a rocket-type combustion chamber.

It is the general object of this invention to provide a centrifugal pump by which an interrupted or pulsating flow of a combustion liquid may be produced. Such interrupted flow, combined with simultaneous ignition, results in a great number of small but very efficient detonations.

To the attainment of this general object, a centrifugal pump is provided in which the outward discharge of the rotor is interrupted several times during each rotation of said rotor.

The invention further relates to arrangements and combinations of parts which will be herein-after described and more particularly pointed out in the appended claim.

A preferred form of the invention is shown in the drawings, in which

Fig. 1 is a sectional side elevation of a centrifugal pump embodying this invention;

Fig. 2 is a transverse sectional elevation, taken along the line 2—2 in Fig. 1;

Fig. 3 is a sectional side elevation similar to Fig. 1 but showing the parts in a different operative relation; and

Fig. 4 is a perspective view showing a pair of centrifugal pumps and a single driving turbine.

Referring to Figs. 1 to 3, the improved centrifugal pump comprises a two-part casing 10 in which a rotor 11 is rotated by a driving shaft 12. The rotor 11 has a plurality of blades 14 separated by discharge passages 15. The blades and passages are preferably of the same circumferential length at the periphery of the impeller and the blades 14 are preferably made hollow for lightness, as indicated at 16.

The casing 10 has a chamber 20 in which the rotor 11 revolves with close clearance. The chamber 20 is surrounded by an outwardly expanding discharge passage 21 and by a spiral volute 22, which volute is discharged through an outlet pipe 24.

One part of the casing 10 is provided with a plurality of segmental closure members 30, extending across the chamber 20 and just clearing the ends of the impeller arms or blades 14.

The liquid to be pumped is supplied at the axis of the pump through a feed pipe 33 (Fig. 2) and flows freely into the passages 15 between the impeller blades 14. The liquid tends to move outward along the passages 15 in the usual way under the influence of centrifugal force, and when the blades 14 are in the position shown in Fig. 3,

the liquid is freely discharged through the passage 21 and volute 22 into the outlet pipe 24.

When, however, the blades 14 are in the position shown in Fig. 1, such outward flow is obstructed, as the outer ends of the passages 15 are closed by the segmental closure members 30. The discharge of the pump is thus interrupted every time the impeller reaches the position shown in Fig. 1, and flow again takes place every time the impeller reaches the position shown in Fig. 3.

An interrupted or pulsating discharge thus takes place through the outlet pipe 24, and the frequency of interruption depends on the number of blades on the impeller, taken in connection with the speed of rotation thereof.

In Fig. 4, two pumps P and P' are shown mounted on a single driving shaft and rotated by a single fluid-operated turbine T. With this combination, two combustion liquids may be fed intermittently to a single combustion chamber, and the interruptions of feed may be caused to take place simultaneously and at equal time intervals.

Having been thus described, the invention is not to be limited to the details herein disclosed, otherwise than as set forth in the claim, but what is claimed is:

A centrifugal pump for effective delivery of liquid in quantity and having a two-part casing and an impeller rotatably mounted in said casing and having an even number of wide-end blades extending from adjacent the axis to the periphery of said impeller and an equal number of alternating outwardly expanding delivery passages of substantially the same peripheral length at their outer ends and extending from adjacent the axis to the periphery of said impeller, and an equal number of thin segmental shields mounted on one part of said casing and extending across said casing and closely clearing the periphery of said impeller, and said shields being of substantially the same peripheral length as said blades and said passages.

ESTHER C. GODDARD,
45 Executrix of the Last Will and Testament of
Robert H. Goddard, Deceased.
